United States Patent Office.

W. H. AND L. WADDELL, OF CHURCHVILLE, VIRGINIA.

Letters Patent No. 79,035, dated June 16, 1868.

IMPROVEMENT IN CHURNS.

The Schedule referred to in these Letters Patent and making part of the same.

Be it known that we, W. H. and L. WADDELL, of Churchville, and county of Augusta, and State of Virginia, have invented a new and useful machine for operating the common upright "staff-and-dash" churn; and we do hereby declare that the following is a full, clear, and exact description of the construction and operation of the same, reference being had to the annexed drawing, making a part of this specification.

Our invention consists of a wheel, B, on which is attached a roller, C, which works in a slot in the lever-beam A. This lever-beam works on a pivot at the point a, being attached to a bench or other fastening. The staff of the churn is attached to the lever-beam, at D, by a small bolt, or at any other suitable point, according to the height to which it is designed to lift the stuff.

When the wheel is put in motion by the crank, the roller C moves in the slot, carrying the lever-beam, and, consequently, the churn-staff, up and down with every revolution of the wheel.

What we claim as our invention, and desire to secure by Letters Patent, is—

The combination of the wheel, roller, and lever-beam, as above described, for the purpose of operating the common churn.

WILLIAM H. WADDELL.
LYTN. WADDELL.
